CLOCK OR SIMILAR ARTICLE

Walter R. Avis, Rosemont, Pa.

Application September 21, 1955, Serial No. 38,009

Term of patent 14 years

(Cl. D42—7)

FIG. 2.

FIG. 1.

FIG. 3.

Fig. 1 is a front elevational view of a clock or similar article showing my new design;

Fig. 2 is a side elevational view thereof, and

Fig. 3 is a front perspective view thereof on a reduced scale.

The dominant features of the design reside in the portion shown in full lines. The back of the clock comprises essentially a plane surface having the necessary cut-outs for access to the clock mechanism.

I claim:

The ornamental design for a clock or similar article, as shown and described.
